UNITED STATES PATENT OFFICE.

GEORGE P. CRAGIN, OF ADA, ASSIGNOR TO W. R. SMITH, OF FERGUS FALLS, AND IDA L. CRAGIN, OF ADA, MINNESOTA.

BLACKING-BOX HOLDER.

SPECIFICATION forming part of Letters Patent No. 378,954, dated March 6, 1888.

Application filed June 23, 1887. Serial No. 242,278. (No model.)

To all whom it may concern:

Be it known that I, GEORGE P. CRAGIN, a citizen of the United States, residing at Ada, in the county of Norman and State of Minnesota, have invented certain new and useful Improvements in Blacking-Box Holders; and I do hereby declare the following to be a full, clear, and exact description of the invention, such as will enable others skilled in the art to which it appertains to make and use the same.

My invention relates to certain improvements in blacking-box holders, and has for its object to provide a simple, cheap, and effective device for the purposes stated in which the empty blacking-boxes can be easily removed therefrom and full boxes, with their covers removed, substituted and secured therein, in which the cover of the holder can be applied in such a manner as to be easily opened or closed, secured in either of said positions, and held out of the way when the box is uncovered.

My improvements consist in the construction and combinations of parts, hereinafter disclosed in the description and claims, which permit the metal cover to be supported and slid upon the upper surface of the holder and be forced against wedge-shaped projections, so as to limit its movement and lock it either in its open or its closed position; also, a cavity or opening is formed in the holder for receiving the box and may be covered beneath with a separate plate; also, the box is secured in the cavity or opening by means of a thumb-screw passing through the forward end of the holder.

In the accompanying drawings, Figure 1 represents a plan view of the holder with the cover open, the blacking-box in place with its cover removed, and with one side edge broken away to show the groove for holding and guiding the sliding cover; Fig. 2, a longitudinal section on line $x-x$ of Fig. 1, and Fig. 3 a transverse section on line $y-y$ of Fig. 1 with the cover closed.

My invention is constructed in the following manner:

The holder A and handle A' are formed integrally and so as to leave an enlarged portion, A², having parallel sides for receiving the cover B. The said holder is also formed with the cavity A³, for receiving a blacking-

box, C, and said cavity is covered beneath by a metal plate, D, tacked or otherwise secured to the under side of the holder A for providing a bottom upon which the box C may rest.

The side edges of the holder A are grooved at a, and the sliding cover B, of sheet metal, is turned downwardly and inwardly at its sides, so as to cause its edges to fit the side grooves, a, of the holder, hold the cover thereon, and permit it to slide from end to end thereof.

The end movements of the sliding cover are limited in both directions by short tacks, brads, or pins a', fastened into the grooves a at or near their ends, and the cover is also arrested at the ends of said movements and clamped upon the holder for holding said cover either open or closed by wedge-shaped projections a² and a³, formed or secured upon the upper surface of the holder. The projection a² is located at the broad or forward end of the holder.

It consists of an inclined strip of suitable material extending across the upper surface of said holder and upon which the forward edge of the cover bears when closed. It presses upward upon the cover and locks the same in place by frictional contact; also, it fills up the space at the end of the cover when the latter is in closed position. The projection a³, upon which the rear end of the cover slides to hold it open, may also be made of any suitable material.

The rear end of the cover is folded under, so as to stiffen it and give a better surface to bear upon the projection a²; also, the edges of said cover which run in the grooves a are doubled over, so as to present smooth surfaces, which will prevent friction as they are moved back and forth.

A projection or hand-hold, B', is riveted or otherwise secured upon the cover B, and permits said cover to be easily moved upon the holder.

The blacking-box C is securely held in place within the cavity A, so that it will not turn or fall out, by a thumb-screw, E, passing through the end of the holder and pressing against the rim of the box. When the box is empty, it can be easily removed from the holder and a full box, with its cover removed, substituted and secured therein. The holder, as is obvious, is substantially constructed and will

last for years. There are no hinges to break off, and the cover may be slid backward and forward upon the holder and securely held thereon, out of the way, when the blacking-box is uncovered and in use.

When the cover is tightly closed, the holder may be put into a valise or trunk, or even into a drawer with clothing, without soiling anything with which it comes in contact, as the blacking-box is completely covered; also, it is flat and may be closely packed or boxed for shipment.

I construct my holders in three sizes—one large, one small, and one intermediate in size—so as to accommodate any and all sizes of boxes of blacking now manufactured and on sale.

Various minor changes may be made in the construction and arrangement of the parts forming my holder without departing from my invention.

Having thus fully described the construc-

tion and manner of using my invention, what I claim as new is—

1. A blacking-box holder provided with a cavity to receive a blacking-box, a handle and wedge-shaped strips, and a cover constructed and adapted to slide upon said block and be locked by said wedge-shaped strips, substantially as described.

2. A blacking-box holder provided with a blacking-box cavity, a handle, wedge-shaped strips and grooves in its edges, a sliding cover fitted at its edges within said grooves, and a thumb-screw for impinging against the blacking box and holding the same in place within said cavity, substantially as described.

In testimony whereof I affix my signature in presence of two witnesses.

GEORGE P. CRAGIN.
